[57] CLAIM

The ornamental design for a housing for a cigarette lighter adapter, as shown and described.

DESCRIPTION

FIG. 1 is a perspective view of a housing for a cigarette lighter adapter showing our new design, it being understood that the connecting cord, side and tip contacts depicted by means of broken lines are for illustrative purposes only and form no part of the claimed design;

FIG. 2 is an elevational view of the left side of the adapter housing, the right side being a mirror image thereof;

FIG. 3 is a plan view of the bottom thereof;

FIG. 4 is a plan view of the top thereof;

FIG. 5 is an elevational view of the front thereof; and,

FIG. 6 is an elevational view of the rear thereof.
